UNITED STATES PATENT OFFICE.

THOMAS M. HYMAN, OF MONTREAL, QUEBEC, CANADA.

CAR VENTILATOR.

Application filed January 14, 1925. Serial No. 2,429.

This invention relates to improvements in ventilators, and more particularly to roof ventilators for railway cars having either the turret or turtle-back types of roofs.

5 The primary object of the invention is to provide a ventilator so constructed and arranged that it will produce a positive suction when the car is moving, even at low speeds in either direction, to extract foul air 10 from the interior of the car.

A further object is to provide a ventilator so constructed and arranged as to positively exclude dust.

15 Various other objects and advantages may be ascertained from the following description.

The ventilator comprises briefly a downwardly opening suction passage leading from the interior of the car and terminating a short 20 distance above the roof and preferably below its inlet end. The ends of the passage are covered by screens through both of which the air flows outwardly. Downwardly curving air ducts or blast passages are provided having 25 flared mouths facing the ends of the car and discharge orifices located at approximately the same plane as the discharge end of the suction passage, the ducts being inclined to the horizontal so that a current of air flowing through either will strike the roof at an angle of less than 90° and flow at high 30 speed between the end of the suction passage and the roof, thus withdrawing air from the car through the suction passage.

35 In the accompanying drawings which illustrate one embodiment of the invention suitable for use with turret type roofs:—

Fig. 1 is a side elevation of the ventilator in position and partly in vertical section on the line 1—1, Figure 2.

Fig. 2 is an end elevation of the ventilator.

Fig. 3 is a vertical cross sectional view of the ventilator on the line 3—3, Figure 1.

Fig. 4 is a bottom plan view of the ventilator.

Fig. 5 is an end elevation, on a reduced scale, illustrating adaption of the ventilator to a turtle back roof.

50 Referring more particularly to the drawings, 11 designates the lower deck of a car roof, 12 the upper deck and 13 the sides of the roof turret in which the usual ventilating openings are provided.

55 In that embodiment of the invention suitable for use with a turret roof, the ventilator projects laterally from the side of the turret

and overhangs the lower deck of the car roof, as clearly shown in Figures 2 and 3, but in the case of a turtle-back roof the ventilator projects upwardly from the roof and is turned 60 downwardly through approximately 180° into proximity with the roof, as shown in Figure 5. The form of ventilator suitable for use with a turret roof comprises a base plate 14 for attachment to the turret side wall and 65 having a suitably shaped opening 15 protected by a wire screen 16 of suitably fine mesh. A hood is provided which has a roofing wall 17 sloping outwardly and downwardly from the plate 14 from above the level of the top 70 of the opening 15 to a level below the bottom of the opening and joined to a bottom wall 17a which projects outwardly from the base plate from below the opening 15, said bottom wall having a screened opening 20 forming 75 an outlet for the hood. The upper part of the hood is supported by end walls 18 which preferably are vertical and project at right angles from the plate 14 to which they and the hood are attached by flanges 19. The 80 hood and the end walls form a suction passage having a laterally directed inlet and a downwardly directed outlet so that the passage turns through approximately 90°. The bottom opening 20 of the hood is provided 85 with a substantially horizontal wire screen 21. Tubular casings, forming air ducts or blast passages 22, are provided at each end of the hood, being arranged between the bottom wall 17a and the lower longitudinal edges 90 of the end walls 18 and have flared mouths 23 opening toward the opposite ends of the car, the ducts inclining downwardly from their mouths toward the transverse central plane of the hood so as to restrict the suction passage toward its outlet. The discharge ends 95 of these ducts are located in substantially the same plane as the bottom opening 20 of the suction passage and are preferably of equal or greater width. The inclination of 100 the ducts is such that a current of air flowing through either will impinge upon the lower deck of the roof at an acute angle and at a point substantially beneath the adjacent edge of the suction passage opening, the angle of 105 impingement being such that the current of air naturally flows between the end of the suction passage and the lower deck of the roof across the passage opening so as to create a suction capable of withdrawing air from 110 within the passage, which withdrawn air is replaced by air flowing through the screen

16 from the interior of the car. The space between the bottom of the ventilator and the roof constitutes an air channel through which air may flow across the outlets of the suction 5 and blast passages and into which channel these passages discharge. By reason of the 10 inclination of the lower walls of the blast passages relatively to the roof, this channel is tapered from its ends toward the intermediate portion into which the passages discharge. Preferably the outlet of the suction 15 passage is elongated transversely of the direction of flow of air emerging from the blast passages in order to obtain the best suction effect.

When the car is in motion even at relatively 20 low speeds, air is gathered by the advancing open end of the channel and by reason of the taper in the channel is slightly compressed so as to flow with considerable velocity directly across the open end of the suction 25 passage. In the same way the forwardly facing blast passage gathers air which is compressed and discharged into the channel at a point in advance of the suction passage outlet and in an inclined direction. The inclination of this air current is assured by the 30 inclination of the passage and is such that it impinges upon the air current flowing through the channel or upon the car roof and directs the flow of air away from the mouth of the suction passage. The combined action 35 of the two air currents produces a strong outward flow of air in the suction passage, which serves to keep air in the channel from eddying into the suction passage, and also serves to blow dust away from the mouth of the suction passage. It is practically impossible for 40 dust to pass through the ventilator owing to the fact that the movement of air under the hood is always outward from the car and owing also to the fact that the movement of dust in order to pass through the ventilator is contrary to the action of gravity. Any dust 45 which may be driven through the outer screen by a gust of air falls back through the screen either with or without striking the under surface of the hood.

In the illustrated embodiment of the invention, the suction passage turns through approximately 90° and the inner screen 16 is vertically disposed solely because of the type of roof to which it is applied. When the

ventilator is applied to a turtle-back type of roof the suction passage will turn through 55 approximately 180° and the inner screen will be disposed approximately horizontal, as shown in Figure 5, but in other respects the ventilator will be substantially as described. In either case the fundamental features will be the same, also the principle of operation, the difference being merely in the length and shape of the suction passage to accommodate the ventilator to the different types of roofs. 60

While the invention has been described only 65 in connection with railroad cars it will be understood that its use is not thus limited.

While the constructions described and illustrated are at the present time preferred, 70 it will be understood that many modifications of detail may be made without departing from the spirit of the invention.

Having thus described my invention, what I claim is:—

In a ventilator, a base plate having a 75 screened opening forming an inlet, a hood mounted thereon and presenting; a roofing wall sloping outwardly and downwardly from the base plate from above the top of the inlet to a level below the bottom thereof, a 80 bottom wall projecting outwardly from the base plate from below the bottom of the inlet with its outer end joined to the lower end of the said roofing wall, said bottom wall having a screened opening forming an outlet, end 85 walls extending at right angles to the base plate between the latter and the upper part of the roofing wall with their respective lower longitudinal edges spaced from the said bottom wall, and tubular casings disposed 90 within the spaces between the bottom wall and the said end walls to provide air ducts for directing a current of air transversely of the opening in the said bottom wall and having flared mouths disposed in advance of the 95 end walls and having their respective discharge ends located in the same plane as the outlet of the hood, said casings inclining downwardly from their mouths towards the transverse central plane of the hood to restrict the passage of the latter towards its outlet; said hood being attached to the base plate by flanges on the walls thereof. 100

In witness whereof, I have hereunto set my hand.

THOMAS M. HYMAN.
